US00D756194S

(12) **United States Design Patent**
Brown et al.

(10) **Patent No.:** US D756,194 S
(45) **Date of Patent:** ** May 17, 2016

(54) **DOOR HANDLE**

(71) Applicant: **KABA ILCO CORP**, Rocky Mount, NC (US)

(72) Inventors: **Jeff Brown**, Murphy, NC (US); **Didier Kaczmarek**, Rocky Mount, NC (US)

(73) Assignee: **KABA ILCO CORP**, Rocky Mount, NC (US)

(**) Term: **14 Years**

(21) Appl. No.: **29/516,824**

(22) Filed: **Feb. 6, 2015**

(51) LOC (10) Cl. **08-06**

(52) U.S. Cl. **D8/308**

(57) **CLAIM**

The ornamental design for a door handle, as shown and described.

DESCRIPTION

FIG. 1 is a perspective view of a door handle;

FIG. 2 is an end view of the door handle;

FIG. 3 is an opposite end view of the door handle;

FIG. 4 is a top plan view of the door handle;

FIG. 5 is a front view of the door handle;

FIG. 6 is a bottom view of the door handle; and,

FIG. 7 is a rear view of the door handle.

The broken lines shown represent unclaimed subject matter and form no part of the claimed design.

1 Claim, 3 Drawing Sheets
